CAN COVER

John M. Hothersall, Brooklyn, N. Y., assignor to
 American Can Company, New York, N. Y., a
 corporation of New Jersey

Application October 2, 1933, Serial No. 691,871

3 Claims. (Cl. 220—97)

The present invention relates to improvements in friction can cover plugs, and has more particular reference to the conformation of the plugs to avoid tight nesting and sticking together when they are arranged in stacked formation.

Tight nesting and sticking together of stacked plugs interferes with their proper feeding from a magazine to various operating parts of machines as for example can closing machines wherein the plug is applied to a filled can. In such feeding operations the lowermost plug is removed from the stack and obviously deep nesting or sticking together of adjacent plugs presents serious obstacles to an effective feeding action. The present invention eliminates the difficulty by preventing such deep nesting and sticking together.

An object of the present invention is the provision of a friction plug having its peripheral edge formed so that it supports the adjacent superimposed plug and prevents deep nesting, sticking or wedging together when in stacked formation.

A further object of the invention is the provision of friction plugs having a conformation designed to present line contact as contradistinguished from surface contact when the plugs are in stacked formation.

Yet another object of the invention is to provide non-sticking friction plugs with a yielding section designed to spring back under a pressure applied to adjacent stacked plugs so that only a line contact is had between any two plugs, thus preventing deep nesting, sticking and wedging of the stacked plugs.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a friction plug embodying the present invention; and

Fig. 2 is a section of two stacked plugs drawn to a larger scale.

The preferred embodiment of the present invention comprises a friction plug 11 having a central drawn panel with a bottom wall 12 which merges by means of a rounded peripheral corner 13 into an upstanding friction wall 14. The upper edge of the wall 14 is preferably curled outwardly, upwardly and inwardly to form an open or unfinished curl 15, the bounding walls of which leave an annular open space 16.

When the plugs 11 are stacked as shown in Fig. 2, the panel corner 13 of the top plug makes a mere line contact with the curl 15 of the low-

er plug, each plug in the stack resting upon and being supported by the plug immediately below. The curl 15 being springy by reason of its open construction serves as a cushion and pressure tending to squeeze the plugs together even when excessive can only deform the curl 15 and perhaps close the annular opening 16. The line contact still obtains, however, and such cushioning is effective to prevent deep nesting, wedging and sticking together of the plugs even under such extreme conditions.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A friction plug comprising a central panel portion having a continuous cylindrical friction wall terminating in an outwardly and thence inwardly curled edge which provides supporting surfaces for similar plugs when stacked one adjacent the other, the curl of each plug in the stack supporting the panel portion of the adjacent plug to prevent deep nesting, sticking and wedging together, said outward curl providing a shoulder for the extraction of the friction plug.

2. A friction plug comprising a cupped central panel portion having a rounded corner and a friction wall, said wall terminating in a continuous curl formed outwardly from said friction wall and thence inwardly and which provides a support for an adjacent plug when similar plugs are stacked together, the said curl of each plug engaging and supporting the rounded corner of the panel portion of the plug adjacent and preventing deep nesting, sticking and wedging together by presenting only a tangential peripheral contact of one plug with another.

3. A friction plug comprising a cupped central panel portion having a rounded corner and a friction wall, said wall terminating in an open continuous curl formed outwardly from said friction wall and thence inwardly and which provides a yielding tangential peripheral engagement with the rounded corners of the panel portions of adjacent plugs when similar plugs are stacked together, such yielding line engagement preventing deep nesting, sticking and wedging between adjacent friction plugs when in stacked formation.

JOHN M. HOTHERSALL.
